MASSACHUSETTS.

ELECTRIC TRACK-SWITCH-OPERATING MECHANISM.

SPECIFICATION forming part of Letters Patent No. 760,656, dated May 24, 1904.

Application filed January 20, 1903. Serial No. 139,866. (No model.)

To all whom it may concern:

Be it known that we, CHARLES W. SQUIRES and JAMES B. SQUIRES, citizens of the United States of America, and residents of Springfield, in the county of Hampden and State of Massachusetts, have invented certain new and useful Improvements in Electric Track-Switch-Operating Mechanism, of which the following is a full, clear, and exact description.

This invention relates to track-switch controllers, and more especially to that class thereof in which the switch-tongue is shifted by an oppositely-effective electromagnetic device most advantageously comprised in two or more axially-alined solenoid-coils, the movable core for and in common to which is directly connected with the track-switch tongue, while an electric current is induced 15 into either of the solenoid-coils or other electromagnetic provisions by a distributing-switch disposed at the side of the roadway and having the operation thereof controlled by the current which drives the motors of the car 20 and which passes through and is subject to government by the controller of the car.

Switch operating and controlling apparatuses of the class to which this invention pertains are shown and described in Letters Patent of the United States granted to us February 6 and April 17, 1900, Nos. 642,943 and 25 647,637, and in patent applied for July 2, 1902, under Serial No. 114,790.

A leading object of this invention is to provide and combine in a switch-operating mechanism of the general character aforementioned a solenoid or electromagnetic device in a circuit which may be included in connections between the main feed-wire and the 30 electric track-switch-operating device, so that the distributing-switch to cause the unimpaired feed-current directly to either of the track-switch electromagnetic devices will be always operated with sufficient power to certainly move the distributing-switch to its proper circuit-establishing positions and conditions, avoiding imperfect contacts and the detrimental results attendant thereupon, such electromagnetic controlling means for the dis-

tributing-switch being, however, secondary 50 in its operations to and under the control of a primary member, also preferably a solenoid or electromagnetic device comprised in current connections whereby the current therethrough may be that which passes through 55 the car and its controller and motor, and all whereby the operation and management of the whole apparatus is within the control of the motorman on the car.

This invention differs from those in the 60 aforementioned patents, although being in some respects subordinate thereto, in that here the distributing-switch is operated in its positive and reliable manner by the power-current, (which is the same current as is utilized 65 directly upon the switch-throwing mechanism,) it being only necessary to depend upon the current which has passed through the car controller and motor for actuating the electromagnetic switch devices which bring in 70 the power-current for actuation of the distributing-switch, it being appreciated that while the current which has passed through the controller and motor of the car and perhaps been utilized to operate the lights and 75 heaters thereof is sometimes comparatively weak and at all times variable, and therefore not entirely reliable for operating the electromagnetic devices for the distributing-switch, which latter works against more or 80 less mechanical resistance. The current through the car-controller is, however, entirely adequate for the actuation of the electromagnetic device which insures the switching in of the main line-current directly to the 85 electromagnetic device which operates the distributing-switch of our new apparatus.

Under one phase of this invention the current which controls the direct power-current, which operates the distributing-switch must 90 be of greater strength than that required for lighting and heating the car, so that it will be operative only when a power-current is applied to and through the motor or motors of the car.

The invention comprises in a car-switch mechanism, in combination, a track-switch, oppositely-effective electromagnetic track-

switch-operating devices, a power feed-wire, normally open circuit connections between the feed-wire and said track-switch-operating devices, a distributing-switch for establishing 5 connection from the power-wire to said electromagnetic track-switch-operating devices, and an electromagnetic track-switch-operating device comprised in circuit-conductors between the feed-wire and a return-wire arranged 10 to be completed through the medium of a car and its controller.

The invention, furthermore, comprises, as secondary to the foregoing, a combination of the distributing-switch for establishing circuits direct from the power-wire in reverse directions or oppositely effective through the coils of the track-switch electromagnetic operating device, a switch controlled and actuated by the current coming thereto through and 15 from the car and its controller and motor for sending the strong power-current through the electromagnetic distributing-switch-operating device, and a still further switch arranged in conjunction with suitable conductors, which is 20 operative to shunt the current from the main power-wire out from the distributing-switch electrically-operated device, deenergizing the latter and yet leaving the power-current still for an interval in connection through the one 25 or the other of the coils of the electric track-switch-operating device, and, furthermore, combined with the foregoing are mechanical devices operative upon the deenergizing of the distributing-switch electrical device for 30 mechanically throwing the distributing-switch after the proper interval into its circuit-opening position.

Our invention is clearly illustrated in the accompanying drawings, in which similar 40 characters denote similar parts, and in which—

Figure 1 shows a front view of the distributing-switch mechanism, the terminal plate having been removed. Fig. 2 is a side view looking from the right of Fig. 1, with the terminal 45 plate in position. Figs. 3 to 10, inclusive, are diagrams illustrating a series of successive positions of the operating parts and showing the connections as well as the flow of the currents for energizing the track-switch solenoids.

The mechanism embodying the invention is preferably located in a box secured in a convenient place near the track-switch in order to reduce the resistance to the operating-currents to a minimum and where it may be 55 within access for inspection and regulation when necessary.

In the drawings the inclosing sides of the box have been omitted, the back board only being 60 shown in connection with the mechanism carried thereby, this board being designated by the numeral 10. Secured upon the board 10 is an electromagnet 11, preferably made in the form of a solenoid, having a gravitational core 12, which is raised whenever the solenoid

11 is sufficiently energized and which will drop again as soon as the current is shut off therefrom or falls below a certain given amperage, so that when the car is rolling over the track when only the amount of current necessary for lighting and heating the car is used the solenoid 11 will not be energized sufficiently to raise the core 12. At its upper end the core 12 is connected with a lever 13, the switch-arm 13' of which is adapted to contact with either of the metallic strips 14 15, the former of which is in constant electrical connection, through a conductor 16, (see Fig. 3,) with one terminal 17 of an electromagnet or solenoid 18, which is also secured upon the base-board 10 and has preferably a gravitational core 19 (see Fig. 2) so arranged that when the solenoid 18 is energized the core 19 will be raised and with it a vertically-movable slide 20. (See Figs. 1 and 2.) This slide 20 constitutes the 85 medium whereby the oppositely-effective solenoids for operating the track-switch are energized alternately to throw said switch back and forth, the controlling mechanism being so organized that each and every upward movement will result in throwing the track-switch tongue into a different position—viz., right, left, right, left, &c.—so that if the switch is originally in proper position for an approaching car an application of motor-power will result in throwing the switch into its wrong position, and it will therefore be necessary to make another application of motor-power to throw the switch back again.

The slide 20 may be guided on screws 21, passing through slots 22 in the slide and held in the solenoid-supports 23, and it may be connected with the core 19 by a horizontal extension 20', secured thereto, while a guide-strip 24 and clip 25 may serve to support the 100 left side of the slide, as shown in Fig. 1.

The functions of the slide 20 are, first, to alternately make and break the circuits alternately established between the track-switch solenoids; secondly, to throw a switch in these 110 circuits to prevent sparking and to assist in closing these circuits at the right time, and, thirdly, to set in operation a mechanism whereby the core 19 will be at first permitted to gravitate at a comparatively quick speed and subsequently be retarded sufficiently to permit a car to pass the track-switch before the circuit to the solenoid controlling the track-switch is broken, a circumstance which would result in leaving the latter free to move at will, 115 and thus be liable to cause accidents and derailments.

The mechanism for making and breaking the circuits alternately established for the track-switch solenoids to throw the switch-tongue back and forth comprises an insulated plate 30. (See Figs. 2 and 3 to 6, inclusive.) Disposed on this plate are a series of terminals 31 32 33 34, preferably equidistant from each other and around a common center, so 125

that a contact member or switch 35 may connect the opposite pairs of terminals consecutively. The member 35 is in the present instance intermittently rotatable on a stud 35' and consists substantially of a blade, which may be positioned on an insulated cylindrical carrier 36—as, for instance, by pins 37, projecting forwardly therefrom—and it is provided with two sets of pins 38 39, respectively, 5 adapted to be engaged by the slide 20, above mentioned, in such a manner that when the slide moves upward the carrier 36 will be rotated one-eighth, this result being accomplished by the upper face 40 of a bunter 41, secured to or forming a part of the slide 20, striking one of the four pins 38 and after 10 turning the carrier 36 one-eighth of a rotation sliding past said pin to the limit of its upward stroke. The pins 39, which are also four in number, are placed midway between the pins 38, but in a different plane therefrom, so that when one of the pins 38 has served its 15 purpose of rotating the carrier to the proper position during the upper movement of the slide 20 one of the pins 39 will be in position to be engaged by the lower face 42 of a bunter 43, also forming a part of the slide, the bunters 41 and 43 also being in different planes and moving in alinement with the pins 38 39, 20 respectively. Furthermore, the bunter 43 is so disposed that it will cause the proper amount of rotation of the carrier before the slide 20 has completed its downward stroke. Hence it will be understood that when the 25 member 35 is horizontal, as shown in Figs. 1, 3, and the slide 20 is now moved to the limit of its upward stroke, the member 35 will rapidly pass the position shown in Fig. 4 and be placed as shown in Fig. 5, thus electrically connecting the terminals 32 and 34. Likewise inasmuch as the full downward movement of the slide will result in rotating the carrier 36 for another eighth of a rotation it follows that the member 35 will then 30 occupy a vertical position or at right angles to that shown in Fig. 3, thus leaving the terminals 31 32 33 34 independent or isolated as before.

The mechanism for performing the second 35 function of the slide 20—viz., that of throwing a switch to assist in closing the circuits for the track-switch solenoids at the proper time—comprises a lever 50, the switch-arm 50' of which is adapted to contact with the terminal 51 or to sever its connection therewith. The preferred device for properly shifting the switch-arm 50' is clearly shown in Fig. 1, in which 52 denotes a link pivotally supported on the arm 50 and provided with a pin 53, adapted to be engaged by the upper face of a bunter 54 during the last period of the upward movement of the slide 20—viz., after the slide has substantially completed its work in rotating the carrier 36. The link 52 is also 40 provided with another pin 55, adapted to be

engaged by the lower face of the bunter 54 during the downward movement of the slide and when the latter has substantially completed its work in rotating the carrier 36 for another eighth of a revolution. 70

The mechanism for accomplishing the third function of the slide—viz., the retardation of the downward movement thereof after it has reached the limit of its upward stroke and after the solenoid 18 has ceased to be energized—includes what may be termed a “rack” 60, secured to the slide and movable therewith. (See Figs. 1 and 2.) The upper end of this rack is preferably provided with notches 61 62 63, adapted successively to engage pins 64 65 66, respectively, of a disk 67, carrying a pair of independent spring-pressed pawls 68 69, the former of which is in engagement with a ratchet-wheel 70, while the latter serves to turn the ratchet-wheel 71, 75 both ratchet-wheels being preferably similar in size. The ratchet-wheel 70 is secured upon a spindle 72, which carries near its other end a gear 73 in engagement with a pinion 74, considerably smaller than said gear, while the 80 ratchet 71 is attached to a sleeve 75, loosely mounted on the spindle 72 and attached to a pinion 76, so as to move in unison therewith. The gear 76 is also in engagement with a lantern-pinion 78, secured on a spindle 79, 85 which has an escapement-wheel 80, the movement of which is intermittent by virtue of a pawl 81, provided with a pendulum-weight 82. It follows therefore that when the disk 67, to which an oscillatory movement is imparted by the reciprocation of the rack 60, is moved in the direction of arrow *a* both pawls 68 and 90 69 will slide over the teeth of the ratchet-wheels 70 71, respectively, until the pawl 68 will be raised entirely out of engagement with its wheel 70, this result being achieved by a cam-plate 83, formed on or to the frame of the retarding mechanism and engaging a pin 84, carried by said pawl 68 and projecting through an aperture 85, provided therefor in the disk 60, this aperture being of sufficient size to permit the pawl to be disengaged from the ratchet, as will be readily understood. 95

The organization of the mechanism above described is therefore such that the leverage 100 exerted by the pawl 69 onto the gear 77 and the pendulum actuated thereby is greater than that exerted by the pawl 68, and hence it is evident that when the pawl 68 is raised and the pawl 69 operates the pendulum the 105 vibrations of the latter will be more rapid than they can be when the pawl 68 is operating the same, provided, of course, that the power applied to the pawls is uniform in both cases. 110

Now, since the upward movement of the slide 20 results in rotating the disk 67 sufficiently to bring the pawl-pin 84 nearly to the rear end of the cam-plate 83, the pawl 69 115 will be active in rotating the disk 67 back 120 125 130

again at a comparatively high rate of speed, thus permitting the rack 60 and the slide 20 to gravitate rapidly for a certain distance, at least until the upper face 90 of a secondary bunter 91, also carried on the slide 20, has arrived at a position below one of the pins 39, so that when the solenoid 18 is again energized before the slide has descended sufficiently to reestablish contact between the switch-arm 50' and the terminal 51 the carrier 36 may have rapidly imparted to it another eighth of a revolution to reverse the circuits leading to the track-switch solenoids, as will be hereinafter described.

15 The system of permanent electrical connections between the several terminals is fully illustrated in Fig. 3, in which F denotes a feed-wire or source of energy connected with a fuse *f*, from which a conductor *g* leads to one end of the solenoid 18 and also to the strip 14. The other end of the solenoid 18 is connected, through a conductor *h*, with both the terminals 32 31 and also with the switch-arm 13'. The strip 15 is connected, through 20 a conductor *i*, with the switch-arm 50', and from the strip 51 a conductor *j* leads to terminal 33, which is connected, through a conductor *k*, with one of the track-switch solenoids I, while the other terminal 34 is in electrical communication with the track-switch solenoid II, both of these solenoids being oppositely effective for throwing the track-switch tongue T in opposite directions. The return-wire from the track-solenoids I and II 25 is indicated by I and is grounded on the track. The permanent connections for the solenoid 11 consist of a conductor *m*, leading from a metal strip *n* of an insulating-block B to one terminal of the solenoid 11, the other terminal 30 of which is connected, through a conductor *o*, with another metal strip *p*, also secured upon the block B. The strip *n* is connected, through a conductor *q*, with the main trolley-wire, which is herein indicated by W, having 35 a certain portion P insulated from the main wire, cut-outs being preferably employed to accomplish this result.

Although the wire section P is, as has just been stated, insulated from the main wire W, yet electrical energy is supplied to it from said wire, but indirectly—viz., it being connected, through a conductor *r*, with the metal strip *p* above mentioned, so that consequently whenever the section P is in any manner connected with the rail or grounded the current must necessarily energize the solenoid 11.

Now the section P is grounded whenever the controller of a car running on the track 40 is operated to give power to the motors, the current passing through the trolley-pole D of the car, thence to the controller E and its rheostat, thence to the car-motor M, and through the car-wheels to the rail which constitutes the return or negative wire.

From the foregoing it will be seen that when the switch-tongue is not in proper position for an approaching car, the trolley-wheel of which is running on the section P, it will only be necessary to operate the controller of the car so as to apply power to the motor, whereupon the current will become effective to raise the core of the solenoid II, which action will result in establishing a circuit for operating one of the track-switch solenoids to shift the track-switch tongue into its required position.

Inasmuch as the solenoid 11 serves only for the purpose just mentioned, it may properly be called the "primary" current, while both the solenoid 18 and the circuits controlled thereby may be called "secondary."

The operation of our improved mechanism is clearly shown in Figs. 3 to 10, inclusive, in which Fig. 3 illustrates all the connections existing between the several terminals and the solenoids with their respective connections, while in the succeeding figures only the active currents are traced to facilitate a clear understanding thereof.

In Fig. 3 no current is active and the circuits are all open. When the motorman of the car operates the handle of the controller E, a current is immediately established, as follows: from the main wire W, through conductor *q*, strip *n*, wire *m*, solenoid 11, wire *o*, strip *p*, wire *r*, section P, trolley-pole D, controller E, motor M, and the track-rail or return. This current will energize the solenoid 11 and raise its core, thus bringing the switch-arm 13' into contact with the strip 15, as shown in Fig. 4, and establishing a secondary current, as follows: wire W, plate *n*, wire F, fuse *f*, wire *g*, solenoid 18, wire *h*, arm 13', strip 15, wire *i*, arm 50', wire *j*, wire *k*, solenoid I, wire *l*, and track.

This current therefore energizes the solenoid 18, the core of which will instantly rise to its highest position, carrying the slide 20 with it and turning the member 35 from the position shown in Fig. 3 to that shown in Fig. 5, so that Fig. 4 in reality represents only an instantly transitory condition, the movement of the core of the solenoid being sufficiently rapid to immediately open the circuit leading to the solenoid I and closing that for solenoid II. (See Fig. 5.) The solenoid II is now in a closed circuit, so that the switch-tongue T will be thrown over. The next step will be the action of the motorman shutting off the power, thus releasing the solenoid 11, the core of which will immediately drop, and thus return the arm 13' to its normal position, (see Fig. 6,) which also shows the solenoid 18 out of circuit, so that its core, with the slide 20, is now at liberty to descend, this movement being at first rapid and then retarded in a manner above described. The particular object of the retardation will now be apparent, viz: It permits the circuit for the solenoid to remain

closed for a sufficient length of time to hold the switch-tongue until the car has had a chance to pass over the switch, a period of about fifteen seconds in actual practice, after 5 which the member 35 will be moved to break the circuit by the slowly-descending slide 20 and into the position shown in Fig. 7, when all circuits are again open, and no waste of power can take place in consequence.

- 10 Let it now be supposed that the switch-tongue had been shifted into the wrong position when the power was applied. Then there is still a remedy to correct the undesired or wrong condition by merely shutting off the 15 power long enough to allow the solenoid 11 to drop its core and also to permit the slide 20 to make its rapid portion of descent until the bunter 91 will have arrived below the carrier 36, (at which point the rapid descent 20 stops and the slow descent begins,) whereupon another application of power will result in bringing the member 35 into position to connect the next pair of terminals, either 32 34 or 31 33, as the case may be, thereby energizing the other track-switch solenoid, and consequently reversing the switch again. It is of course evident that the switch-tongue may thus be caused to be thrown back and forth as long as the trolley is in contact with 25 the section P and as often as the controller opens and closes the power-circuit when the car is thus placed, each power admission throwing the member 35 at least one-eighth of a revolution.
- 30 Referring again to Fig. 6, it is here shown that the solenoid II is energized, the energization continuing until the core of solenoid 18 has arrived near the end of its descent, when all the circuits are open and the member 35 35 is vertical, as seen in Fig. 7. The next application of motor-power will in the same manner as previously described throw the arm 13' into contact with the strip 15, thus again energizing the solenoid 18, raising the 40 slide 20, and turning the member 35 past the position of Fig. 8 into that shown in Fig. 9, so that now the terminals 31 and 33 are electrically connected, and thus establish the circuit for solenoid I. When now the core of 45 solenoid 11 is released by shutting off the power-current, the arm 13' will be disconnected from the strip 15, (see Fig. 10,) thus shunting the solenoid 18 and permitting its core and the slide 20 to descend, as before, so that when the slide 20 has arrived at the lower 50 end of its stroke the member 35 will again be in the position shown in Fig. 3, leaving all the circuits again open.

55 In conclusion attention is invited to the fact that while the mechanism above described constitutes an automatic device for opening the circuits for the track-switch solenoids the primary solenoid is an expedient whereby the secondary circuits may be established 60 from a car on the track and that when it may

be deemed preferable a hand-operated lever may be substituted for throwing the arm 13' into and out of engagement with the strip 15. It is also obvious that many changes may be made in the construction of the several parts 70 without in any way interfering with the object and gist of our invention.

Having thus described our invention, what we claim, and desire to secure by Letters Patent, is—

75 1. In a track-switch-operating mechanism, in combination, a track-switch, oppositely-effective electromagnetic track-switch-operating devices, a power feed-wire, normally open circuit connections between the feed-wire and said track-switch-operating devices, a distributing-switch for establishing connection from the power-wire to said electromagnetic track-switch-operating devices, and an electromagnetic distributing-switch-operating device 80 comprised in circuit-conductors between the feed-wire and a return-wire arranged to be completed through the medium of a car and its controller.

85 2. In a track-switch-operating mechanism, the combination with a primary member, and a secondary solenoid controlled by the movement of the primary member, of a track-switch 90 movably controlled by successive similar movements of the secondary solenoid-core.

95 3. In a track-switch-operating mechanism, the combination with a primary solenoid and a secondary solenoid controlled by the movement of the core of the primary solenoid, of a track-switch reversible by each successive 100 similar movement of the secondary core.

105 4. In a track-switch-operating mechanism, the combination with a primary member, a secondary solenoid controlled by the movement of the primary member, of a pair of oppositely-effective solenoids alternately energized during successive upward movements of the secondary core.

110 5. In a track-switch-operating mechanism, the combination with a primary solenoid having a gravitational core, of a secondary solenoid, means for energizing the secondary solenoid during the upward movement of the primary core, and a track-switch solenoid controlled by the movement of the secondary core.

115 6. In a track-switch-operating mechanism, the combination with a primary solenoid having a gravitational core, of a secondary solenoid having a gravitational core controlled by the movement of the primary core, and a track-switch solenoid energized during alternate movement of the secondary core.

120 125 7. In a track-switch-operating mechanism, the combination with a primary solenoid having a gravitational core, and a secondary solenoid having a gravitational core controlled by the movement of the primary core, of a pair of oppositely-effective solenoids alternately controlled by the movement of the secondary core.

8. In a track-switch-operating mechanism, the combination with a primary solenoid having a gravitational core, a secondary solenoid controlled by the movement of the primary core, of a pair of oppositely-effective solenoids alternately energized during successive upward movements of the secondary core.

9. In a track-switch-operating mechanism, the combination with a primary member, a secondary solenoid, and means for energizing the secondary solenoid by the movement of the primary member, of a track-switch solenoid controlled by the movement of the secondary core, and a mechanism for retarding the return movement of the secondary core, during its movement after the release of the secondary core.

10. In a track-switch-operating mechanism, the combination with a primary member, a secondary solenoid, and means for energizing the secondary solenoid by the movement of the primary member, of a track-switch controlled by the movement of the secondary core, and a mechanism for retarding the return movement of the secondary core during its movement after the release of the secondary core.

11. In a track-switch-operating mechanism, the combination with a primary member, a secondary solenoid, and means for energizing the secondary solenoid by the movement of the primary member, of a pair of oppositely-effective solenoids alternately energized during successive upward movements of the secondary core, and a mechanism for retarding the return movement of the secondary core during its movement after the deenergizing of the secondary solenoid.

12. In a track-switch-operating mechanism, the combination with a primary solenoid, a secondary solenoid controlled by the movement of the primary core, a slide controlled by the secondary core, of a mechanism for retarding the slide during its movement after the release of the secondary core.

13. In a track-switch-operating mechanism, the combination with a primary solenoid, a secondary solenoid controlled by the movement of the primary core, a slide controlled by the secondary core, of a mechanism for variably controlling the movement of the slide during its return stroke.

14. In a track-switch-operating mechanism, the combination with a primary solenoid, a secondary solenoid controlled by the movement of the primary core, a slide controlled by the secondary core, of a differential-speed and variable-power-resistance mechanism for variably controlling the movement of the slide during its return stroke.

15. In a track-switch-operating mechanism, the combination with a primary solenoid, a secondary solenoid controlled by the movement of the primary core, a slide controlled by the secondary core, of an escapement mech-

anism for retarding the slide during its movement after the release of the secondary core.

16. In a track-switch-operating mechanism, the combination with a primary solenoid, a secondary solenoid controlled by the movement of the primary core, and a slide controlled by the secondary core, of an escapement mechanism and means for varying the movement of the escapement-wheel thereof, variably controlling the movement of the slide during its return stroke.

17. In a track-switch-operating mechanism, the combination with a primary solenoid, a secondary solenoid controlled by the movement of the primary core, a slide controlled by the secondary core, of an escapement mechanism and differential gearing for variably controlling the movement of the slide during its return stroke.

18. In a track-switch-operating mechanism, the combination with a primary solenoid, a secondary solenoid controlled by the movement of the primary core, and a slide controlled by the secondary core, of a pawl movable with said slide for engaging said retarding mechanism.

19. In a track-switch-operating mechanism, the combination with a primary solenoid, a secondary solenoid controlled by the movement of the primary core, a slide controlled by the secondary core, and a rack carried by said slide, of an escapement mechanism, a pawl-carrier in engagement with said rack, a pawl on said carrier for engaging said retarding mechanism, and means for maintaining said pawl out of engagement with said retarding mechanism during the initial return movement of the secondary core.

20. In a track-switch-operating mechanism, the combination with a primary solenoid, a secondary solenoid controlled by the movement of the primary core, a slide controlled by the secondary core, and a rack carried by said slide, of an escapement mechanism and a pawl-carrier in engagement with said rack, a pawl on said carrier and for engaging said retarding mechanism, and a stationary cam.

21. In a track-switch-operating mechanism, the combination with a primary solenoid and a secondary solenoid controlled by the movement of the primary member, of a pair of oppositely-effective solenoids alternately energized during successive upward movements of the secondary core, of a distributing-switch member controlled by the movement of the secondary core, controlling the track-switch solenoids.

22. In a track-switch-operating mechanism, the combination with a primary solenoid, a secondary solenoid controlled by the movement of the core of the primary solenoid, of a pair of oppositely-effective track-switch solenoids alternately energized during successive upward movements of the secondary core, a distributing-switch member controlled by

the movement of the secondary core, intermittently rotatable to make and break the circuits of the track-switch solenoids alternately.

5 23. In a track-switch-operating mechanism, the combination with a primary solenoid, and a secondary solenoid controlled by the movement of the core of the primary solenoid, of a pair of oppositely-effective solenoids alternately energized during successive upward movements of the secondary core, a distributing-switch member and means for shifting said member to close the circuits of the track-switch solenoids during the upward movement 15 of the secondary core.

24. In a track-switch-operating mechanism, the combination with a primary solenoid, and a secondary solenoid controlled by the movement of the core of the primary solenoid, of a pair of oppositely-effective solenoids alternately energized during successive upward movements of the secondary core, a distributing-switch member and means for shifting said member to close the circuits of the track-switch solenoids during the upward movement 25 of the secondary core, and means for shifting said member to operate the track-switch circuits during the downward movement of the secondary core.

30 25. In a track-switch-operating mechanism, the combination with a primary solenoid, and a secondary solenoid controlled by the operation of the primary solenoid, of a pair of oppositely-effective track-switch solenoids to be alternately energized during successive upward movements of the secondary core, and distributing-switch member, of a rotatable distributing-switch-member carrier, and means for intermittently rotating said carrier.

40 26. In a track-switch-operating mechanism, the combination with a primary solenoid, and a secondary solenoid controlled by the operation of the primary solenoid, of a pair of oppositely-effective track-switch solenoids, to be alternately energized during successive upward movements of the secondary core, and a distributing-switch member, of a rotatable switch-member carrier having sets of pins disposed in different planes, a slide controlled by 50 the secondary core and having bunters for engaging said pins, alternately, during the movements of said slide in opposite directions respectively.

27. In a track-switch-operating mechanism, the combination with a primary solenoid, a secondary solenoid controlled by the primary one, and a pair of oppositely-effective track-switch solenoids, to be alternately energized during successive upward movements of the secondary core, of a reciprocating slide movable in one direction to energize the track-switch circuits and movable in the other direction to break the track-switch circuits.

60 28. In a track-switch-operating mechanism, the combination with a primary solenoid, a

secondary solenoid controlled by the primary one, and a pair of oppositely-effective solenoids, to be alternately energized during successive upward movements of the secondary core, of a reciprocating slide and means for 70 energizing one of the track-switch solenoids during a partial movement of said slide in one direction, and subsequently shunting the secondary solenoid.

29. In a track-switch-operating mechanism, 75 the combination with a track, of a car movable thereon, and having a controller, a track-switch, and a main trolley-wire, comprising a live section insulated therefrom, of a primary solenoid controlled by a circuit including the 80 insulated trolley-wire section, a secondary solenoid, controlled by the movement of the primary solenoid, and a track-switch solenoid controlled by the movement of the core of the secondary solenoid.

30. In a track-switch-operating mechanism, the combination with a track, a car movable thereon, and having a controller, and a track-switch, of a main trolley-wire, comprising a live section insulated therefrom, a primary solenoid controlled by a circuit including the insulated trolley-wire section, and a conductor 90 for supplying energy to said insulated section subsequent to its passage through said primary solenoid.

31. In a switch-controlling device for railroads in combination—a primary circuit in which are comprised a solenoid-magnet and an insulated section of conductor, a secondary circuit in which are comprised another solenoid-magnet, a circuit-changing switch, and a track-switch-operating magnet; means by which the primary circuit and solenoid-magnet are utilized to establish a current in the secondary circuit, and means by which the current so established in the secondary circuit is again broken by the operation of the circuit-changing switch comprised in the secondary circuit.

32. In combination—a primary circuit in which are comprised a solenoid-magnet and an insulated section of conductor, a secondary circuit in which are comprised another solenoid-magnet, a circuit-changing switch and a track-switch-operating magnet; means by which the solenoid in the primary circuit on 110 being energized, establishes a current through the secondary circuit; and means by which the solenoid in the primary circuit, on being 115 deenergized, shunts the current so established in the secondary circuit, from the solenoid-magnet comprised in the said secondary circuit.

33. In combination—a primary circuit in which are comprised a solenoid-magnet and an insulated section of conductor; a secondary 125 circuit in which are comprised another solenoid-magnet, a circuit-changing switch and a track-switch-operating magnet; means by which the solenoid, in the primary circuit on being energized, establishes a current through 130

the secondary circuit; means by which the solenoid in the primary circuit, on being deenergized, shunts the current so established in the secondary circuit; and means by which 5 the current in the secondary circuit is again broken by the operation of the circuit-changing switch comprised in the said secondary circuit, substantially as set forth.
